CLEANING WASTE LINES

Edwin Wiklund, Chicago, Ill.

Application January 8, 1940, Serial No. 312,814

10-Claims.

(Cl. 4—255)

My invention relates to cleaning waste lines, such as drains, fixtures, fittings and pipes associated with or forming a part of plumbing installations.

The principal object of the invention is the provision of improved means for removing stoppages in lines such as those associated with plumbing installations.

Another object is the provision of such means so designed that partial stoppages may be removed and a pipe may be rendered thoroughly clean.

In carrying out my invention, I may proceed in several ways, depending upon the particular character of the obstruction and the equipment with which the obstruction is associated. The same general principle is utilized, however, whatever the circumstances may be. In general, a stoppage or partial stoppage is associated with a pipe or drain connected with a piece of equipment such as a lavatory sink. I proceed in accordance with my invention by closing off the entire space which includes the pipe or drain in which the stoppage has occurred, thereby establishing a closed system, and fill this space up with water. I then apply a strong suction and the material, such as waste matter which is responsible for the clogging, is constrained to move in accordance with the suction which has been applied to the closed system. I then apply pressure to effect a reverse movement. By alternate movements, i. e., resulting alternately from suction and pressure and wherein the water acts as a ram during the pressure movement, the stoppage is quickly relieved.

More specifically, in the case of a stoppage as in a drain pipe from a lavatory basin, I provide means for closing of all normal drains, overflow openings, and the like, and fill the entire drain system, above the place where the stoppage has occurred, with water. I provide a pump system including a cylinder and piston, the cylinder forming a part of the closed system so that on reciprocation of the piston of the pump, the alternate actions take place of the pump applying suction, and causing the water in the system to act as a ram against the stoppage. As the stoppage is relieved, the water is forced with a strong jet action to clean out the area thoroughly in which the stoppage occurred, and, if desirable, additional water, either hot or cold, may be introduced to thoroughly clean all parts of the system. I also provide means, as will be described, for increasing the pressure on a stoppage where such is required.

Specific objects and features of the invention will be brought out in connection with the following description taken with the accompanying drawings, wherein

Fig. 1 is an elevational view showing a pre-

ferred pump structure of a type particularly adaptable for use in accordance with my invention;

Fig. 2 is an enlarged fragmentary vertical section taken through the pump and illustrating structural features thereof;

Fig. 3 shows the equipment as it is employed in accordance with one embodiment of the invention for the cleaning of a drain of an ordinary lavatory basin;

Fig. 3A is a fragmentary plan view showing the closure member as applied to the basin in Fig. 3;

Fig. 4 shows the application of the invention for cleaning a drain of a sink such as an ordinary kitchen sink, which is not provided with an overflow;

Fig. 5 shows the invention as it is employed for cleaning a drain, as of a toilet fixture;

Fig. 6 is a plan section taken on the line 6—6 of Fig. 5, showing some details of structure of the closure member used;

Fig. 7 shows the manner in which the invention is used in cleaning a urinal fixture;

Fig. 8 is a plan view of a form of equipment used as a closure member, as in carrying on the operation illustrated in Fig. 6;

Fig. 9 is a sectional view thereof taken on the line 9—9 of Fig. 8, looking in the direction of the arrows;

Fig. 10 is a plan view of a closure member such as may be employed over certain types of overflow openings; and

Fig. 11 is a sectional view thereof taken on the line 11—11 of Fig. 10.

For convenience, I shall first describe the principal portions of the equipment used in accordance with my invention and thereafter show the manner in which this equipment is employed in accomplishing its objects.

Looking first at Figs. 1 and 2, I show there a special form of pump structure comprising, as a framework, an upper casting member 12, intermediate casting member 13, and lower casting member 14, between which cylinders 16 and 17 are placed, the entire frame structure being held together by means of tie rods 18.

The upper cylindrical member 16 comprises a cylinder of a hand pump within which a piston 19 is reciprocable through a piston rod 22 and handle 23. The rod 22 extends through a vertical aperture in the upper casting member 12, and a suitable type of packing gland 24 is provided to produce an adequate seal. A lower integral cylindrical projection 26 on the casting member 12 serves to facilitate the sealing action, steadies the assembly, and limits the upward movement of the piston. It will be noted that the piston comprises a stacked assembly of leathers and metal disks through which a threaded portion of the rod 22 extends, and nuts supplied above and

below the gland 24.

below the stacked members comprising the piston serve to hold the piston together as a unitary structure and also to mount it on the rod. Other suitable constructions, however, may be employed. I have not shown a gasket or other form of packing between the upper part of the cylinder 16 and the upper casting member 12, but it is understood that suitable means is employed to cause the joint between the cylinder 12 and the casting to be leakproof.

An interiorly threaded boss 27 is provided on the upper casting member 12 for attachment of a suitable hose coupling. This is the sole opening to that portion of the cylinder 16 above the piston 19, with the exception of a bleeder valve 28, the function of which will be described later. A bleeder hole 29, permanently open to atmosphere, is provided on that portion of the cylinder 16 below the piston 19 to permit free operation of the piston.

Concentrically disposed within the lower cylinder 17 is a smaller cylinder 31. Both of these cylinders are sealed at top and bottom except for openings which will be described. Within the smaller cylinder 31 is a piston 32 having connected thereto a rod 33 extending up into the lower portion of cylinder 16 through a packing gland 34. A head 36 on the upper part of the rod 33 is adapted to engage the piston 19, the construction and disposition of parts being such that when the pistons 19 and 36 are both at their lowermost positions, the head 36 is slightly spaced from the lower nut holding the piston 19 to the piston rod 22.

The space 37 between cylinders 31 and 17 is adapted as a reservoir to contain a supply of a hydraulic fluid, and mechanism is provided for withdrawing the hydraulic fluid from the space 37 and delivering it under pressure beneath the piston 32, and for releasing the hydraulic fluid beneath the piston 32 back to the space 37 when desired.

Supported in the frame is a long, relatively narrow cylinder 38 containing a piston 39 operated by a rod 41, to the top of which a knob or hand piece 42 is secured. Suitable means are provided to prevent loss of hydraulic fluid around the piston 39. As shown, the construction of the piston 39 is such as to have a suitable sealing effect, it being understood, of course, that the portion of the cylinder above the piston 39 is substantially open to atmosphere to prevent binding. Beneath the piston 39 is a passageway 43 and a passageway 44 leading, as shown, to the bottom of piston 32. Connected to the passageway 43 is a passageway 46 leading to the reservoir space 37. A pair of check valves is provided such that, on the upstroke of piston 39, hydraulic fluid is drawn from the space 37, and, on the down stroke, this hydraulic fluid is delivered to the lower part of cylinder 31. Thus by operating the piston 39, the piston 32 and rod 33 may be caused to rise, thereby applying pressure to the bottom of piston 19 and raising it also against such resistance as may be encountered. It will be noted that an opening 47 is provided at the upper part of cylinder 31. This permits free upward movement of piston 32, but also has the function of acting as a safety in that, when piston 32 clears the opening 47, continued operation of the piston 39 will have no further effect on the piston 32 because of the by-passing of hydraulic fluid into the space 37. It will be noted that there is a passageway 48

communicating with the space 37 and the lower part of piston 32. Within the passageway 48, I provide a seat for a needle valve 49. Opening the needle valve 49, therefore, permits hydraulic fluid to flow from the lower part of cylinder 31 whereby the piston 32 may be permitted to return to its lower position.

Structural details and features described above all cooperate in securing the unusual results 10 which my invention makes possible. To facilitate handling the equipment shown in Figs. 1 and 2, I provide a stirrup 51 secured to the lower casting member 14 whereby to permit engagement by the foot when the pump is operated.

15 Looking now at Figs. 8 and 9, I show there a body member 52 of general dish shape having an annular flange 53 to which a gasket or sealing member 54 is secured. A pair of interiorly threaded bosses 56 are provided near the upper 20 portion of the body member for the attachment of fittings, and fastening members 57 extend through the body member for attachment of the device to an opening in plumbing equipment such as at the drain of a lavatory sink. The fastening member 57 has a hook-like lower projection with an indicating head 58 to show the direction in which the hook-like member extends. A wing nut 59 is threaded on the shank portion of the fastening member 57, a suitable gasket 30 61 being provided between the wing nut and the upper surface of the body member. The gasket member is so designed as to fit over any minor irregularities which may be encountered, but which at the same time will form a good seal. 35 Soft rubber with some "sponge" character has been found suitable, provided, however, that it should not have exterior pores.

Another form of closure member is shown in Figs. 10 and 11. This comprises a relatively flat 40 body member 62 with an upwardly extending interiorly threaded boss 63 and a fastening member 64 substantially centrally disposed in the body member and having the same general arrangement and structure as the fastening member described in connection with the closure member of Figs. 8 and 9. The same general character of gasket is used.

One manner of using the equipment and 45 practicing the invention may be explained by reference to Fig. 3. Here a lavatory sink 66 has the usual lower drain to which a soil pipe 67 is attached. An overflow at 68 of generally conventional character is also shown. Assuming a stoppage in the pipe 67, a closure member such as shown in Figs. 10 and 11 is secured over the overflow opening, and a flexible hose 69 is secured between the boss 63 and a water faucet 71, using suitable fittings for attaching the flexible hose at its two ends. At the bottom of the sink, at 50 the main drain, a closure member 72 is attached, which may be generally similar to the closure member shown in Figs. 8 and 9 except that only a single fitting attaching boss is employed. The identical closure member shown in Figs. 8 and 9, however, may be employed and one of the openings therein plugged with a suitable plug fitting. A flexible hose 73 is then attached between the closure member and the upper portion of the pump at the boss 27. The hoses 69 and 73 may be made of a good grade of rubber and fabric, and should be strong enough to stand relatively high pressures or suction without collapsing. Connections are now established for clearing 55 stoppage of the pipe 67.

The first step is to completely fill the closed system which is established by closing the overflow and the drain opening and securing the hoses 69 and 73 in position. Preferably first the handle 23 of the pump is raised, the valve 11 is opened, and the system is filled with water. By pressing down on the release 28, air trapped in the line may be released. If desired, any other suitable outlet for the release of air may be employed, such as in the closure member mounted over the overflow opening. When the closed system has been filled with water, the faucet 11 may be closed, although I may provide a check valve at 74 in the hose 69 to prevent pressure on the system from forcing waste water back into the pipe lines. At this time, the handle 23 is pushed down sharply and this causes a sharp pulling or suction action on the material which is responsible for the stoppage. The handle then is immediately pulled up, thereby producing a strong ram action on the material causing the stoppage and tending to force it through. Several reciprocations of the handle are preferably made to entirely clear out the stoppage; and, if the water is permitted to be delivered continuously from the faucet 11, a complete flushing of the pipe 67 will take place.

Fig. 4 shows an installation such as might be employed on a kitchen sink. Here the drain is shown at the bottom and the closure member, which may be identical with that shown in Figs. 8 and 9, is secured over the drain opening. In this form of sink, as a rule, an overflow is not provided and, accordingly, I connect the hose 69 directly from the twin fitting 16 to the closure member, the hose 73 being connected to the pump and to the closure member in a manner substantially identical with that shown in connection with Fig. 3. To operate the system, the same general method is employed as described in connection with the Fig. 3 installation.

In Fig. 5, the invention is applied to a usual type of toilet fixture. Here a Y-connection 77 may be provided for attachment of the hose 73 leading to the pump structure and for attachment to a bent pipe 78 carrying a specially designed closure member 79 at the bottom thereof. The other connection to the fitting 77 is adapted for connection to a water supply, and a hose connection such as 69 may be employed, if desired.

In connection with the arrangement shown in Fig. 5, it may be noted that the bent character of the pipe 78 permits the closure member 79 to be presented to the drain opening at a suitable angle, it being understood that the specific shape of the drain openings in different fixtures will vary. The closure member 79 comprises preferably a generally cone-shaped, soft rubber member having a central opening through which the pipe 78 extends and radial ribs, as shown in Fig. 6, to provide strength. If the stoppage is merely a temporary one, it may be unnecessary to employ water for flushing purposes. The fitting 77 is preferably provided with a check valve so that, on the pressure stroke of the pump, the water will be delivered with a ram action through the fixture and in the direction of the stoppage rather than through the water connection.

In the arrangement shown in Fig. 7, a urinal fixture 81 having the usual bottom drain is cleaned or flushed by reversing the closure member 79 on the pipe 78. The annular portion of the member may be held so as to seal the open-

ing. The same Y-connection 77 used in Fig. 5 may be used, and the same general method of operation may be used.

The description of the operation made hereinabove with respect to Fig. 3 is in general illustrative of the method employed independently of the fixture and equipment which may be encountered. I have already pointed out that preferably a suction stroke is first used, followed immediately by a pressure stroke which hits the stoppage with a ram action to force it through. At times the nature of the stoppage may be such that alternate suction and pressure action, that is, action which tends to move the stoppage backward and forward to loosen it, is ineffective. At such times, it may be necessary to apply a straight, even pressure to force the material causing the stoppage to a portion of the plumbing system of greater diameter, such as a stand pipe. In this case, the hydraulic portion of the pump is operated, thereby giving greater pressure than is possible with simple hand action. A single movement of the hydraulic piston may be sufficient to relieve the stoppage, but, if it is serious, continued pressure may be necessary to move the waste material along a relatively long line. Under these circumstances, the hydraulic pressure is released by operating the needle valve 49, the system is filled with an additional amount of water equivalent to that displaced by the upward movement of the piston, the valve 49 is closed, and the hydraulic piston again used. This series of operations may be continued until the material causing the stoppage is forced entirely from the line.

It must not be assumed that equipment shown and described is of advantage only when a stoppage has occurred which entirely stops or clogs a drain or waste line. Pipes, drains and the like which have accumulated some waste material so that in effect the diameter of the pipe or drain is reduced, may be cleaned out by the flushing action made possible through the arrangement of the pump and closure members described. In this kind of a flushing action, either hot or cold water may be employed.

Another illustrative use may be shown by considering an installation of the general character of that shown in Fig. 3. When an overflow opening is provided in a lavatory sink, there is very often considerable accumulation of grease, soap, hair, and other foreign materials in the line running from the overflow opening down to the pipe 67. This accumulation not only may clog up the overflow opening but it is frequently a source of bad odors and may be a source of infection if it is not taken care of. By flushing this opening out, for example by attaching the hose 73 to the closure over the overflow opening, this portion of the sink may be thoroughly cleaned.

It will be understood that, while the types of closure members shown may be used for substantially any type of installation, still, specific details, such as fastening members, the gasket arrangement, the shape, the number of openings and the like may be changed without departing from the spirit and scope of the invention. Furthermore, while I refer mostly to plumbing in homes and apartments, it is to be understood that the invention may be applied to any usual types of plumbing installations, whether industrial or conventional home installations, although, to be sure, some adjustments as to some of the fittings may be necessary.

What I claim as new and desire to protect by Letters Patent of the United States is:

1. In a system for cleaning drain pipes and the like, a pump comprising a cylinder having a single passageway at the top thereof, said passageway functioning both as an intake and outlet, a piston within said cylinder, a piston rod secured to said piston, and a handle secured to the piston rod for reciprocating the piston, the arrangement being such that upward movement of the piston causes a pressure action through said passageway, and means for placing said passageway in communication with a plumbing drain.

2. In a system as defined in claim 1, the addition of hydraulic means for actuating said pump piston on its pressure stroke.

3. In a system as defined in claim 1, the addition of hydraulic means for actuating said pump piston on its pressure stroke, said hydraulic means comprising a cylinder placed below the first-mentioned cylinder, a piston in said cylinder, a rod adapted to engage the first-mentioned piston at the lower side thereof, and pump means for pumping hydraulic fluid into the second-mentioned cylinder beneath the piston therein.

4. In a system as defined in claim 1, the addition of hydraulic means for actuating said pump piston on its pressure stroke, said hydraulic means comprising a cylinder placed below the first-mentioned cylinder, a piston in said cylinder, a rod adapted to engage the first-mentioned piston at the lower side thereof, pump means for pumping hydraulic fluid into the second-mentioned cylinder beneath the piston therein, and means for by-passing hydraulic fluid when the hydraulic piston reaches a predetermined upper position.

5. In a system of the character described, a closure member, means for releasably but firmly attaching said closure member over a drain opening, whereby to seal a drain line from all connections except its normal sewer connection, means for introducing water through the closure member whereby the drain line may be completely filled with water above a point at which a stoppage has occurred, a pump having a single passageway serving as both an intake and outlet when the pump is operated, and means utilizing said closure member for connecting said passageway of the pump with the drain line, whereby actuation of said pump will serve through water contained in the drain pipe to alternately apply suction and pressure to said drain pipe at a point where a stoppage has occurred.

6. Apparatus for use in a system of the character described, comprising a pump structure having a frame, a cylinder supported vertically in the frame, a piston vertically reciprocable in said cylinder, a handle exterior of the cylinder and connected by a piston rod to said piston, means near the bottom of the pump and secured to the frame for engagement by the foot, whereby simple manual operation of the piston is permitted, and a single threaded passageway through said cylinder near an upper portion thereof.

7. Apparatus for use in a system of the character described, comprising a pump structure having a frame, a cylinder supported vertically in the frame, a piston vertically reciprocable in said cylinder, a handle exterior of the cylinder and connected by a piston rod to said piston, means near the bottom of the pump and secured to the frame for engagement by the foot, whereby sim-

ple manual operation of the piston is permitted, a single threaded passageway through said cylinder near an upper portion thereof, a cylinder axially disposed with respect to said first-mentioned cylinder and placed below the same, a piston reciprocable within said second-mentioned cylinder, manually controlled hydraulic means for moving said second-mentioned piston, and a connection whereby movement of the second mentioned piston will cause movement of the first-mentioned piston on its pressure stroke.

8. Apparatus for use in a system of the character described, comprising a pump structure having a frame, a cylinder supported vertically in the frame, a piston vertically reciprocable in said cylinder, a handle exterior of the cylinder and connected by a piston rod to said piston, means near the bottom of the pump and secured to the frame for engagement by the foot, whereby simple manual operation of the piston is permitted, a single threaded passageway through said cylinder near an upper portion thereof, a cylinder axially disposed with respect to said first-mentioned cylinder and placed below the same, a piston reciprocable within said second-mentioned cylinder, manually controlled hydraulic means for moving said second-mentioned piston, a connection whereby movement of the second-mentioned piston will cause movement of the first-mentioned piston on its pressure stroke, and means for limiting the upward movement of the second-mentioned piston.

9. Apparatus for use in a system of the character described, comprising a pump structure having a frame, a cylinder supported vertically in the frame, a piston vertically reciprocable in said cylinder, a handle exterior of the cylinder and connected by a piston rod to said piston, means near the bottom of the pump and secured to the frame for engagement by the foot, whereby simple manual operation of the piston is permitted, a single threaded passageway through said cylinder near an upper portion thereof, a cylinder axially disposed with respect to said first-mentioned cylinder and placed below the same, a piston reciprocable within said second-mentioned cylinder, manually controlled hydraulic means for moving said second-mentioned piston, a connection whereby movement of the second-mentioned piston will cause movement of the first-mentioned piston on its pressure stroke, and means for limiting the upward movement of the second-mentioned piston.

10. In a system for cleaning drain pipes and the like, a pump comprising a cylinder, a piston vertically reciprocable in the cylinder, a rod projecting upwardly from the piston axially thereof, a handle outside of the cylinder and secured to said piston rod, and a passageway in the cylinder so placed that downward movement of the piston causes a suction action on the system of which the pump forms a part.

EDWIN WIKELUND.
